TAILPIPE THRUST AUGMENTOR

William Raphael Travers, Madeira, Ohio, assignor to
General Electric Company, a corporation of New
York

Application March 30, 1955, Serial No. 497,862

1 Claim. (Cl. 60—39.72)

This invention relates to fuel burners and, more particularly, to a device for burning fuel in the exhaust duct or tailpipe of a jet engine.

Under certain operating conditions, it is desirable to augment the thrust output of a jet engine. Numerous methods of augmentation have been known and used in the prior art. One method of augmentation is by injecting and burning additional fuel in the exhaust duct or tailpipe of the jet engine downstream of the turbine wheel. Burning has been accomplished in the prior art by providing a pilot or primary burner in the tailpipe in combination with second fuel injection means so that combustion is initiated in the pilot or primary burner and is caused to spread to the fuel injected by the second fuel injection means. Burning is thereafter continuously maintained by injecting additional fuel.

The velocity of the combustion products and excess air in the tailpipe is often greater than the velocity of flame propagation. The use of a pilot burner provides one method of reducing the flow velocity in a portion of the tailpipe sufficiently to permit the burning of fuel to be initiated.

Pilot burners, as heretofore known, reduce the velocity of flow by creating a turbulent condition within the pilot burner which leads to non-uniform mixture of the air and fuel resulting in inefficient combustion both in the pilot burner and the air fuel mixture near the second fuel injection means. A further disadvantage of tailpipe burners as heretofore known is that the amount of fuel burned to obtain a given amount of thrust increase requires the use of an extra fuel pump to fully supply the needs of the tailpipe burner. The high fuel rates are due to the inefficiency in the burning of fuel caused by the turbulence created by the pilot burner. The use of an extra fuel pump is, of course, disadvantageous in aircraft installations where a primary objective is to eliminate as much excess weight as possible. The added fuel pump adds substantially to the weight of the engine.

It is a general object of this invention to obviate the aforementioned difficulties.

Another object of this invention is the provision of a tailpipe thrust augmentor whereby the pilot burner is supplied with air in such a manner that a vortex substantially coaxial with the axis of the tailpipe is formed thereby obtaining a more uniform air-fuel mixture resulting in efficient combustion in the pilot burner and at the second fuel injection means.

It is a further object of this invention to provide a tailpipe thrust augmentor which does not require the use of an extra fuel pump for injecting fuel due to the improved combustion efficiency which reduces the required fuel flow for a given amount of thrust augmentation.

Briefly stated, in accordance with one aspect of my invention, I provide a tailpipe thrust augmentor including a pilot burner and second fuel injection means having means cooperating with the pilot burner for causing a vortex in the pilot burner of the burning air-fuel mixture substantially coaxial with the tailpipe so as to improve

2

the burning characteristics within the tailpipe. Fuel is supplied to the pilot burner and second fuel injection means from a regulator or control valve which meters fuel in proportion to the compressor discharge pressure of the jet engine.

The invention will be better understood from the following description taken in connection with the accompanying drawing wherein, Figure 1 is a longitudinal view, partially in section, of a tailpipe augmentation system of a jet engine mounted in an aircraft; Figure 2 is an enlarged fragmentary cross-sectional view of the pilot or primary burner; and Figure 3 is an end view, partial in section, taken along the lines 3—3 of Figure 1.

Figure 1 shows the tailpipe augmentation system as it may be mounted in an aircraft. The rear portion of a jet engine which may be of the type having a compressor, combustion chamber and turbine in series flow relation is generally indicated at 1. The engine including the rear portion 1 may be mounted in an aircraft as generally indicated at 2. The rear portion of the jet engine 1 comprises a turbine casing 3 and an outer exhaust cone 4 held together at their respective radial flanges 5 and 6 by means of suitable clamping members, as for example, the bolts 7. The outer exhaust cone 4 is connected to a tailpipe 8 at their respective radial flanges 9 and 10 by any suitable clamping means (not shown). The tailpipe 8 is further connected to the extension 11 at the flanges 12 and 13 which may be similarly secured by suitable clamping means (not shown). A variable nozzle, generally indicated at 14, is mounted at the end of the duct formed by the outer exhaust cone 4, tailpipe 8, and extension 11, and may be of any form well known in the jet engine art as shown for example in U.S. Patent 2,630,673, Woll, assigned to the assignee of the present application.

Mounted within the outer exhaust cone 4 and substantially coaxial therewith is the inner cone 15 which may take the form of a frustum of a cone. The annular space 16 defined by the outer exhaust cone 4 and the inner cone 15 serves as an exhaust passageway for the fluid consisting of combustion gases and excess air discharged by the turbine (not shown) mounted within the turbine casing 3. A primary or pilot burner, as indicated generally at 17 and shown in detail in Figures 2 and 3, is mounted at the end of the inner cone 15 and is substantially coaxial with the outer exhaust cone 4 and the tailpipe 8.

The primary or pilot burner 17 comprises a hollowed out or sheltered zone 18 mounted at the end of and within the inner cone 15 and connected thereto by means of the annular portion 19. Although the hollowed out or sheltered zone 18 is shown by way of example as being hemispherical in shape, it is to be understood that other shapes will be satisfactory in practicing the present invention. Extending axially with respect to the center of the inner cone 15 from the annular portion 19 are a plurality of vanes or blades 20 each mounted at substantially the same distance from the extended axis of the inner cone 15 and having substantially the same angle of attack with respect thereto. An annular ring-like member 21 is attached to the end 22 of each of the vanes 20 in order to maintain rigidity of the vanes 20 when the burner is in operation. An annular deflector or scoop 23 is mounted near the ends 22 of the vanes 20 and may be secured for convenience to the periphery of the ring-like member 21.

I also provide fuel supply, injection and ignition means. As illustrated, these means comprise a fuel control regulator 24, the operation of which will be hereinafter described, which is supplied with fuel from the main fuel pump by means of the conduit 25. A conduit 26 supplies air from the jet engine compressor or other pres-

sure sensing point in the engine to the fuel control regulator 24 for control purposes. Fuel is supplied from the control 24 by means of the conduit 27, T 28, branch conduits 29 and 30, the T pieces 31 and 32, and the connecting conduits 33 and 34 of the fuel spray nozzles 35 mounted in the hollowed or sheltered zone 18 of the primary or pilot burner 17 and the fuel spray ring 36.

The fuel spray ring 36 is shown as being circular in shape, but may take other forms which would serve the same purpose. The spray ring 36 is mounted in a plane which is substantially normal to the axis of the inner cone 15 and is approximately coincident with the trailing edge of the primary or pilot burner 17. The fuel spray ring 36 may also vary in position from that shown to obtain efficient burning and under some circumstances it may be desirable to mount it somewhat downstream of the trailing edge of the pilot burner 17. The fuel spray ring 36 communicates with the connecting conduits 34 by means of the conduit extensions 37 and the radial conduit arms 38. The radial conduit arms 38 are rigidly attached to the pilot burner by means of the brackets 39 attached to the ring-like member 21. The radial conduit arms 38 and the brackets 39 may be several in number in order to properly support the fuel spray ring 36. It is to be noted that the conduit extensions 37 connecting the conduits 34 to the radial conduit arms 38 lies between a pair of adjacent vanes 20. A suitable igniter 40, if needed, may be mounted at any suitable location in the hollowed portion 18 of the primary or pilot burner 17. The fuel spray ring 36 is provided with a plurality of apertures 41 about its outer periphery in order to inject fuel into the fluid stream. Although the apertures 41 are shown as spraying fuel radially with respect to the center of the duct, it is to be understood that other spraying directions may be used where desirable.

In operation, the fluid consisting of combustion products and excess air exhausted from the turbine casing 3 passes rearwardly in the exhaust passageway through the annular space 16. A portion of the fluid is directed radially inward through the vanes 20 by the deflector or scoop member 23. The angle of attack of the vanes 20 is such that it causes the formation of a vortex generally indicated at 42 centrally of the pilot burner 17, the axis of which is substantially coaxial with the axis of the tailpipe 8.

During periods when it is desired to augment the thrust output of the engine, fuel is injected through the nozzles 35 into the pilot burner 17. The fuel is intermingled with the excess air of the vortex formed within the pilot burner 17 and forms a very well mixed and uniform air-fuel mixture which may be ignited by the igniter 40 when separate igniter means are found necessary. The burning vortex as generally indicated at 42 within the pilot burner 17 will flow helically out of the open end of the burner 17. A major portion of the fuel is injected into the tailpipe 8 through the apertures 41 of the fuel spray ring 36. Due to the velocity of the exhaust fluid, the spray emitting from the apertures 41 is immediately caused to form a combustible mixture which flows rearwardly in the tailpipe 8. The combustible mixture formed from the fuel sprayed through the apertures 41 is ignited from the burning flame or vortex 42 flowing out of the pilot burner 17. Upon ignition of the fuel injected through the apertures 41, a continuously burning flame occurs in the tailpipe 8 until such time as the fuel flow is completely shut off.

Due to the arrangement of the fuel spray ring 36 and the apertures 41 therein, the fluid flowing through the annular space 16 causes the fuel-air mixture to concen-

trate centrally of the tailpipe 8. The result of this is that the burning in the tailpipe occurs in a core, the outer boundaries of which are indicated by the numbers 43. It will of course be apparent that the advantages of burning the fuel within a core as defined by the boundaries 43 is that the tailpipe 8 is not subjected to the extremely high temperatures of the burning fuel.

As has been previously stated, one of the features of this invention is the elimination of a separate fuel pump for supplying fuel to the augmentation system. Due to the efficient burning within the tailpipe 8 resulting from the formation of the vortex 42, it is possible to eliminate the need of an extra fuel pump and, in its place, use a very simple fuel control 24. The fuel control 24 is of any well known direct ratio type of metering device, such as a bellows type control, which meters fuel flow in direct proportion to and responsive to the discharge air pressure of the air compressor or other pressure occurring within the engine. Although the structural details of such a metering device are not shown, it will be obvious to those skilled in the art that any type of direct ratio pressure responsive metering device will accomplish this result. A control of this type will at all times assure a proper air-fuel mixture since the amount of fuel injected will be in direct proportion to the amount of excess air flowing through the jet engine.

While a particular embodiment of the invention has been illustrated and described, it will be obvious to those skilled in the art that various changes and modifications may be made without departing from the invention, and it is intended to cover in the appended claim all such changes and modifications that come within the true spirit and scope of the invention.

What I claim as new and desire to secure by Letters Patent of the United States is:

A jet engine having, in combination, an exhaust passageway, combustion products and air flowing in said exhaust passageway, a pilot burner including fuel injection and ignition means mounted centrally of said passageway, said pilot burner having a plurality of longitudinally extending peripheral guide vanes, an annular deflector cooperating with said guide vanes to direct a portion of the flow in said passageway through said guide vanes into said burner, the angle of attack of said guide vanes causing the formation of a vortex within the pilot burner, said vortex being substantially coaxial with the exhaust passageway and extending longitudinally thereof, a fuel spray ring mounted within said passageway substantially surrounding the vortex and beyond the vane containing portion of the pilot burner, said fuel spray ring having apertures for spraying fuel into said passageway, means including a regulator having a single fuel control valve for metering fuel to the pilot burner and the fuel spray ring wherein the control valve meters fuel in proportion and responsive to the fluid pressure at a point in the jet engine, the fuel injected from the spray ring being ignited by the pilot burner.
